UNITED STATES PATENT OFFICE.

MARTIN S. CRANE, OF HOBOKEN, NEW JERSEY.

SASH.

1,082,308.

Specification of Letters Patent. Patented Dec. 23, 1913.

Application filed May 16, 1913. Serial No. 768,011.

To all whom it may concern:

Be it known that I, MARTIN S. CRANE, a citizen of the United States, and a resident of Hoboken, in the county of Hudson and State of New Jersey, have invented certain new and useful Improvements in Sashes, of which the following is a specification.

This invention relates to sashes such as are employed for retaining plates of glass 10 in position in windows or doors.

My improvements pertain particularly to sashes for holding large and heavy plates such as are used in show windows or the like, but my improvements are equally applicable to sashes for holding plates of small size and light weight.

The object of my improvements is to provide means of the class specified of simple construction, efficient in operation, easily 20 installed and easily dismantled for removing the plate when desired.

With these ends in view the preferred embodiment of my improvements is illustrated in the drawings accompanying this specification wherein—

Figure 1 is a perspective view showing a sash portion embodying my improvements.

Fig. 2 is a perspective view of a detail of my improvements and Fig. 3 is a perspective view of a further detail thereof. Fig. 4 is a fragmentary perspective view of a portion of one of the members of my device. Fig. 5 is a vertical section illustrating a modification of my improvements.

Before describing the invention in detail I desire to have it understood that the invention is not limited to the particular construction and arrangement of parts which I have illustrated and shall hereinafter 35 describe, and that various changes may be made in the mechanism without departing from the spirit or scope of the invention, and that the phraseology which I employ is for the purpose of description and not of 40 limitation.

While I have illustrated in the principal view, Fig. 1, only a short portion of a sash embodying my improvements and that portion particularly adapted for use on a window sill it will be understood that my improvements are equally adapted for use on the jambs and lintel of the window.

In their preferred embodiment my improvements comprise a plurality of moldings preferably two in number and preferably of metal. The first and principal

molding, 2, may be of some convenient shape generally conforming to a C form. For use on the sill portion of my improved sash and if desired for use on the other portions as well I preferably provide said molding with an upper depressed portion 3 forming a gutter for the reception of moisture from the plate and said gutter is perforated at intervals as at 4 for permitting water to flow therethrough to within the molding. Said molding is provided with a front flange 5 for engagement with the plate 6 to be supported. Parallel with said flange 5 is back wall 7 for engagement with the sill heel 8. Said molding is further provided with base portion 9 preferably at right angles to back wall 7 and for engagement with sill 10. The front portion 11 of said base 9 may be bent upwardly and outwardly for the reception thereunder of another member of my improved sash. Said portion 11 may be provided with channels as 30 for the passage of any water which may settle on its base 9. In addition to holes 4 in the gutter portion 80 of molding 2 I provide other holes 12 for the passage of clamp screws 13 for purposes hereinafter described.

For convenience of construction I preferably form molding 2 of such thickness of sheet metal as may be rolled or drawn to the desired form. For affording added strength and internal support to said molding and for other purposes referred to hereinafter I provide one or more blocks, 14, shown in position in Fig. 1 and detached in Fig. 2, also of C shape and generally conforming in outer profile with the inner profile of molding 2. Said block 14 is provided in its plate abutment or top flange 15 with tapped hole 16 for the reception of screw 13 and in its upright flange 18 with one or more screw holes 19 for the reception of screws 20 for securing said block and molding to sill heel 8. It will be obvious that molding 2 is also provided with holes 21 through its back wall 7 for the passage of screws 20. Said block 14 is further provided with one or more holes 22 in its lower flange for the passage of screws 23 respectively. Said screws 23 may be employed for holding my improved sash in position relatively to sill 10 when said sill is unprovided with heel piece 8. Molding 2 is provided with holes in its bottom flange 9 for the passage of screws 23.

For securing the plate 6 in place I pro-

vide one or more clamp members 24 preferably of L shaped cross section and preferably of about the same length as their coacting blocks 14. Said clamps and blocks are provided with coacting portions, as seat 25 of clamp 24, engaging rib 26 of block 14, whereby said clamp may rock on said block. Clamp 24 is provided with upstanding member 27 for gripping the glass plate or molding or both interposed therebetween and with foot 28 for engagement with screws 13 of block 14. Said foot may be provided with seat 29 for the reception of said screws 13.

15 My second or front molding 31 may be also approximately C shaped and comprises body portion 32, preferably of pleasing design such as the ogee shape shown, terminating at its upper edge in downwardly 20 reaching flange 33 interposed between glass 6 and upstanding member 27 of clamp 24. The lower end of said molding terminates in inwardly reaching flange 34 for entrance under foot or front portion 11 of molding

25 2. Body portion 32 of front molding 31 is provided with scuppers 35 respectively opposite channels 30 of molding 2 for ventilation and whereby water is permitted egress from my improved sash. The described 30 provisions for ventilation and for drainage of water may if desired be omitted from those portions of my improved sash which are employed for lintel and jamb members.

It will be obvious to those skilled in the 35 art that by making molding 2 of sufficient strength and incorporating therein some of the features of block 14, said block may be omitted as shown in Fig. 5. Therein I have shown hole 36 threaded for screw 13 and 40 have provided base 9 with rib 37 corresponding with rib 26 of block 14. It will also be obvious that clamp 24 and molding 31 could if desired be formed in one piece as illustrated in said Fig. 5. This modification 45 however involves some features which are not as convenient as the preferred embodiment of Figs. 1 to 4 inclusive.

My improved device may be installed and operated as follows: A sufficient number of 50 blocks 14 are slid into place within molding 2 and arranged so that the screw holes 19, 22 of said blocks are in line with the corresponding screw holes in molding 2. Thereupon screws 21 or 23 or both are 55 screwed into place in sill heel 8 and sill 10 respectively thus holding said molding and blocks securely in position. These parts having been positioned on sill, jambs and lintel, the plate of glass 6 is inserted with 60 its lower edge resting if desired on spaced supporting blocks preferably two in number, not shown but well known in the art, arranged between blocks 14 and resting on the inner face of molding base 9. Clamp 65 screws 13 having been started into tapped

holes 16 in the blocks, 14, clamps 24 are put into position in engagement with blocks 14 and screws 13 are screwed down to engagement with seats 29 of clamps 24 whereby said clamps are urged to engage said plate 70 6, thereby holding that plate temporarily in place against molding 2 or rocker bearing block 14. Thereupon all the clamp screws 13 on one edge of said plate are slackened sufficiently to permit upstanding portions 75 27 of said clamps to be backed away from the plate to permit the entrance of down-reaching flange 33 of molding 31, which flange is then inserted between clamp portion 27 and plate 6 and lower flange 34 of 80 said molding is inserted under foot 11 of molding 2. Then clamp screws 13 are tightened down, rocking clamps 24 on members 14 respectively and clamping molding 31, plate 6 and molding 2, snugly together (Fig. 85 1). The other edges of plate 6 are then proceeded with in the same manner whereby said plate is securely held in position on all its edges.

I claim:

1. In a device of the class specified the combination of two plate clamping members, a rocker-bearing on one member, a coacting seat on the other member, means for securing the bearing member to a window frame, 95 and means for rocking the other member on the bearing member for clamping the plate against the bearing member.

2. In a device of the class specified the combination of a pair of C shaped moldings 100 arranged face to face, two plate clamping members therebetween, a rocker-bearing on one member, a coacting seat on the other member, means for securing the bearing member to a window frame and means for 105 rocking the other member on the bearing member for clamping the plate against the bearing member, and means accessible from without said moldings for operating said clamping means.

3. In a device of the class specified the combination of a molding, a rocker-bearing block seated in said molding and having a plate abutment, means for securing said molding and block to a window frame, a 115 clamp member having a seat for engagement with said rocker-bearing block and having a plate engaging portion, and means in engagement with said block for urging the plate engaging portion of said clamp member toward the plate abutment of said bearing block.

4. In a device of the class specified the combination of a molding, a rocker-bearing block seated in said molding and having a plate abutment, means for securing said molding and block to a window frame, a 125 clamp member having a seat for engagement with said bearing block and having an upstanding portion, and means in engagement 130

with said block for urging the upstanding portion of said clamp member toward the plate abutment of said bearing block.

5. In a device of the class specified the combination of a molding having a plate engaging portion, a rocker-bearing block seated in said molding and having a plate abutment, means for securing said molding and block to a window frame, a clamp member having a seat for engagement with said bearing block and having an upstanding portion, a second molding having an upper flange for engaging a plate, and means in engagement with said block for urging the

upstanding portion of said clamp member toward the plate abutment of said bearing block to clamp a plate between the upper flange of said second molding and said plate engaging portion of said first molding.

Signed at New York, in the county of New York and State of New York, this 15 day of May, 1913, before two subscribing witnesses.

MARTIN S. CRANE.
